UNITED STATES PATENT OFFICE.

GEORGE W. SWIFT, JR., OF BORDENTOWN, NEW JERSEY.

MACHINE FOR ATTACHING STRINGS TO TAGS, ENVELOPE FLAPS, AND THE LIKE.

Application filed February 18, 1922. Serial No. 537,477.

To all whom it may concern:

Be it known that I, GEORGE W. SWIFT, Jr., a citizen of the United States, residing at Bordentown, in the county of Burlington and State of New Jersey, have made certain new and useful Improvements in Machines for Attaching Strings to Tags, Envelope Flaps, and the like, of which the following is a specification.

10 The invention relates to novel and useful improvements in machines for fastening strings and eyelets to tags, envelope flaps and the like, and more especially to novel and useful improvements in that type of machine in which the string is preliminarily looped about the eyelet position preparatory to fastening.

Objects and advantages of the invention will be set forth in part hereinafter and in 20 part will be obvious herefrom, or may be learned by practice with the invention, the same being realized and attained by means of the instrumentalities and combinations pointed out in the appended claims.

25 The invention consists in the novel parts, constructions, arrangements, combinations and improvements herein shown and described.

The accompanying drawings, referred to 30 herein and constituting a part hereof, illustrate one embodiment of the invention, and together with the description, serve to explain the principles of the invention.

Of the drawings:

35 Fig. 1 is a detail fragmentary elevation of a loop forming mechanism embodying the invention;

Fig. 2 is a horizontal section, taken on line 2—2 of Fig. 1;

40 Fig. 3 is a vertical transverse section taken on line 3—3 of Fig. 1;

Figs. 4, 5, 6 and 7 are views, somewhat diagrammatic of the looping mechanism in different stages of forming a loop;

45 Fig. 8 is an end view of one of the various forms of machine with which the invention may be used;

Fig. 9 is a top plan corresponding to Fig. 8;

50 Fig. 10 is a side elevation, looking at Fig. 9 from the right, with the bed plate in section; and

Fig. 11 is a fragmentary, somewhat diagrammatic view of the washer attaching and eyeleting mechanisms.

55 Fig. 12 is a fragmentary axial section on

an enlarged scale showing advanced positions of certain operating parts shown in Fig. 11.

The invention is directed to improvements 60 in machines for affixing strings to paper tags, envelope flaps and the like, and is directed more especially to a novel mechanism for presenting the string between the tag or envelope flap and reenforcing strip or piece 65 (paper washers being an example), an eyelet being then upset through the reenforcing piece, or pieces, and the tag or flap so as to firmly hold the string in position.

The invention is embodied in a machine 70 of the general type or kind which is shown and described in United States Patent No. 96,125 to William Liddell, dated October 26, 1869, wherein a string is automatically looped preliminarily about the eyelet position, the eyelet plunger then being driven through the loop and the eyelet being thereby upset, and a predetermined length of the string is cut off, and there is then a new feed of the string for the next stringing 75 operation.

Objects of the invention are to provide string looping means which except at the moment of string attaching are located well 80 away and separate from the washer attaching and the eyelet attaching means, so as to provide ample space and to avoid obstruction of those means, leaving them free and open for inspection and adjustment, for clearing out of any jammed material or for 85

any other purposes; to provide for continuous retention of the string by the looping means to avoid the necessity of cumbersome and uncertain mechanism for conveying the string to the looping means after 90

each tag or flap stringing operation; to provide string cutting means which will not cut the string between the string supply and the looping means, thereby contributing to simplicity of structure and certainty of operation in the machine; to provide for forming a loose loop in the free or loose end of a string and moving the loop to and presenting it at the place of fastening only at the moment of fastening the string, washer 100 and eyelet to the flap or tag, at other times maintaining the looping mechanism and the washer presenting and eyeleting mechanism well spaced away from each other. In addition to the foregoing, the invention provides an exceedingly simple and highly effi- 105

cient and very reliable loop forming mecha- 110

nism, useful in the described relation and in other relations as well. Other objects and advantages of the invention will be set forth in connection with the following detailed description of the invention.

Referring now in detail to the present preferred embodiment of the invention, illustrated by way of example in the accompanying drawings, and referring first to the 10 means for forming the loose loop in the free end of the string, said means comprise, or are in cooperation and association with, mechanism for continuously retaining hold and control of the string supply, and also 15 with mechanism for traveling the loop to the eyeleting and washer fastening position, and then moving it away again just previous to fastening the eyelet. The operation in many respects is analogous to the old method 20 used by hand, or manually by the workman, in which the workman gave a turn to the string about the eyelet die plunger, his hand approaching merely for this operation and then moving away from the mechanism. 25 In said embodied form, the traveling carrier 1 is shown as an arm oscillating to and fro with a shaft 2 to which the arm is fixed. The drive for the looping mechanism is operated by this movement of the carrier 1 to 30 and from the eyeleting and washer affixing position.

Means are provided on the traveling carrier 1 for holding the string *a* so that it is carried forward in fixed relation to the loop forming mechanism when the latter is traveling toward the eyeleting and washer affixing position, and for causing it to run through the mechanism of the carrier 1 when it is receding from that position, so that a 35 desired length of string will be provided attached to the tag or envelope flap, and so that this length can be cut off between the eyeleting mechanism and the loop-forming mechanism, thereby making it possible for 40 the looping mechanism to continuously retain hold of the string from the string supply.

In the embodied form of string holding and controlling means, an extension 5 projects laterally from the bottom end of the arm 1, and fixed thereon is a block 6, having formed therein an aperture 7 through which the string *a* passes. Adjacent the apertured block 6 is a flat spring 8 fixed to 55 the block by screws 9, the spring having a recess 10 therein. The string passes from aperture 7 on the outside of the spring to the recess 10, and then passes through the recess and on beneath the spring to the loop forming mechanism.

A supporting, guiding, and aligning device cooperating with the loop forming mechanism is provided, and as embodied, a pin 14 is fixed at 15 in the arm 1. This 60 pin has in its bottom end a guiding aperture

16, in definite and desired relation to the loop-forming mechanism, as shown in Figs. 1 and 2.

In accordance with certain features of the invention, a loose loop is formed in the free 70 end of the string, with the end of the string projecting freely from the loop, as the carrier travels toward the eyeleting and washer affixing station, the loop being completed and presented at the eyeleting station just 75 prior to the advance of the eyelet die plunger, which then comes in through the formed loop.

In the embodied form of said means, a flat 80 circular disc 20 is fixed on a hollow shaft 21 (Figs. 1, 2 and 3), journaled in the bottom part of the carrier arm 1, and fixed to the shaft 21 on the opposite side of the arm 1 is a pinion 22, which is driven to rotate the disc 20. Fixed to the periphery 85 of the disc 20 is a string-engaging, loop-forming finger 23, adapted to engage with the free end of the string *a* during the rotation of the disc 20 to form the loose loop.

Cooperating with the disc 20, as embodied, is a member constituting therewith an annular, peripheral channelway in which the string is laid to form the loose loop, and as embodied, a conoidal disc 24, which is 90 also concentrically hollow, and alined with hollow shaft 21, as shown at 26, presses against the outer flat face of the disc 20.

This member is resiliently pressed against the face of the disc 20, to form the channelway as described and so that at the proper 100 time it may move away to release the loose loop in turning it about the eyelet die plunger and then return to position for forming the next loop. For this purpose, the disc 24 is mounted on a flat spring 27, fixed by 105 suitable means such as screws 28, to a part of the carrier arm 1.

For the purpose of traveling the carrier 1 forward to present the loose loop at the eyeleting and washer-affixing station and 110 then immediately traveling the loop forming mechanism backward away therefrom prior to the eyeleting and washer affixing operation, the disc 24, the disc 20, the pinion 22, and the shaft 21 are laterally recessed as 115 shown at 30, in Fig. 1 and Fig. 8, thereby permitting the traveling carrier arm to move away after the eyelet die plunger has passed through the loose loop.

In the embodied form of means for so 120 swinging the carrier arm 1 to and fro toward and away from the eyeleting position and for actuating the loop-forming mechanism during this travel of the carrier, a gear wheel 39 is fixed on a shaft 40, journaled in the lower part of the carrier arm 1, (Figs. 1 and 3) the shaft 40 having a retaining collar 41 on the opposite side of the arm 1. The gear wheel 39 is in mesh 125 with the pinion 22, and is rotated periodically 130

a predetermined distance, so as to cause the loop forming mechanism to form the loop.

In mesh with gear wheel 40 is an idler gear 44, fixed on a shaft 45, journaled in the 5 arm 1 and having fixed thereto a retaining collar 46 on the opposite side of the arm 1. Meshing with gear wheel 44 is a pinion 47, fixed on a shaft 48, which shaft is journaled in the arm 1. Fixed also on shaft 48 (Figs. 10 3, 8 and 10) is a ratchet wheel 49, with which cooperates a pawl 50, pivoted on a pin 51, which is mounted on a gear wheel 52, which gear wheel is journaled loosely on the shaft 48 on the inner side of the ratchet 15 wheel 49.

Meshing with the gear wheel 52 is a stationary geared sector 53, loosely hung at 15 54 on shaft 2, and held in fixed position by a stud 55, mounted on one of the supports 20 for shaft 2, through which a bolt 56 is screw-threaded into the sector. As a matter of construction the arm 1 is fixed by a bolt 57 to a hub 58, fixed on shaft 2 so that the arm will swing or oscillate with the shaft.

25 Referring now to the embodied form of means for controlling the angular movement and positioning of the gear wheel 39, and thereby of the loop-forming mechanism, there are formed in the inner face of the 30 gear wheel 39 a plurality of detent depressions 68, spaced apart angularly on the gear wheel so that the distance between two adjacent detent depressions will effect one revolution of the loop-forming mechanism. Co- 35 operating therewith is a spring-pressed pin 69 mounted in a detachable block 70, carried in the lower part of the arm 1, and in the path of the depressions 68. Pin 69 is acted on by a spring 70, resiliently pressing it 40 against the face of the gear wheel 39.

Referring to the embodied form of means for mounting and oscillating the shaft 2, the shaft is journaled in standards 73 and 74, supported on and projecting upwardly 45 from the machine frame (Figs. 3, 8, 9 and 10). Fixed to the opposite end of shaft 2 is an arm 75, and pivotally connected at 76 to the end of the arm is a link 77, which link at its opposite end 78 is pivotally connected to a crank disc 79 fixed on a shaft 80. Shaft 80 is journaled in bearings 81 and 82, on the machine frame, and is provided at the other end thereof with any suitable form of drive, such as a belt pulley 83.

55 The manner of operation of the mechanism just described is substantially as follows:—

Referring more especially to Figs. 1, 3 and 8, the mechanism and gearing is proportioned so that gear wheel 39 during the 60 swing of carrier arm 1 in one direction will rotate the distance between one detent depression 68 and the next adjacent one, thereby causing one complete operation of the 65 loop-forming mechanism. The pawl and

ratchet drive holds the loop-forming mechanism stationary during the travel of the carrier arm 1 in the opposite direction. During this movement of the carrier arm with the looping mechanism idle, the desired 70 length of string is measured off from the point where it is fixed under the eyelet, and it is then cut off between the eyelet and the loop-forming mechanism. The loop forming mechanism thus continuously keeps hold 75 of the string from the string supply, and obviates the necessity of providing mechanism for picking up the string again after each string attaching operation and carrying it to the looping mechanism, and successfully 80 reinserting it therein with the attendant cost, mechanical complications and uncertainty of operation.

The carrier arm 1 may be considered as 85 in the position of Fig. 8, at its full travel away from the eyeleting position, and ready to begin its advance toward the left in Fig. 8. At this time the string *a* has its free end in substantially the position of Figs. 1, 2 and 4. As the arm 1 moves forward, the 90 gearing is thereby actuated, and gear wheel 39 is started, springing pin 69 out of the 95 detent 68.

Pin 23 is thus rotated in clock-wise direction in Fig. 1, and bends the free end of 95 the string downwardly beneath it, laying it in the annular peripheral channel way between the discs 20 and 24. In Fig. 5, the position is shown after substantially a half revolution of the loop forming mechanism. 100 In Fig. 6 the mechanism is shown just before the completion of the loop.

It will be noted that by reason of the 105 relation of the parts, including the guiding aperture 16, that the free end of the string in the loose loop is brought upon the inside of the adjacent and contacting part of the string *a* and a complete loose loop of string is formed with the free end loosely held in position by the passing and contacting part 110 of the loop, leaving the loose free end of the formed loop projecting outwardly as shown in Fig. 6. Just as the loop is completed, the spring pin 69 will snap into the 115 next detent depression 68 in gear wheel 39, thus bringing the parts exactly into position for beginning the next looping operation.

In accordance with one feature of the 120 invention, and as already indicated, the eyelet die plunger is inserted through the previously formed loose loop, and then the free end of the loop is grasped to draw it about the plunger, similarly to the old hand operation, and the loop-forming mechanism is retracted and moves away just prior to the 125 eyeleting and washer affixing operation, and in fact is present and in juxtaposition with the eyeleting mechanism and washer presenting mechanism only during the single instant of presenting the loose loop.

So far as concerns most features of the invention, the eyeleting mechanism and the washer presenting mechanism may be of any known or desired form, and as shown herein, and referring primarily to the eyeleting mechanism, one eyelet die mechanism 95 is longitudinally reciprocably mounted in a block 96, carried on the bottom plate 97 of the machine frame. This mechanism is reciprocated in a suitable manner, and as shown, a pin 98 projects therefrom, and pivoted thereto is a link 99, which link is pivotally connected at 100 to a crank 101, the crank being fixed on a shaft 102, journaled at 103 on the machine bed 97. Fixed on shaft 102 is a beveled gear 104, with which meshes a beveled gear 105, fixed on the shaft 80.

The cooperating eyeleting die mechanism, as embodied, comprises a die 110, longitudinally reciprocably mounted in a block 111 and a block 112, fixed on the machine bed 97, and likewise actuated in a suitable manner, and as embodied, a block 113 is fixed on the die plunger 110, having a recess 115 formed therein. Working in the recess 115 is a roller 116, rotatably carried on a shaft 117, journaled in a bearing 118, carried on the machine bed.

Fixed to the shaft 117 is a beveled gear 119, which meshes with a beveled gear 120, fixed on the shaft 80. These mechanisms operate the eyeleting punches in the usual manner. Eyeleting die 110 is provided with the usual plunger 121, and any known or other suitable supply of eyelets is provided, a well-known commercial form thereof being indicated by 123 in Fig. 10.

In accordance with certain features of the invention, reinforcing means are applied to the tag or envelope flap or the like, and these reinforcing devices are usually in the form of washers, applied to either side of the tag or flap. Any suitable form of washer supplying and presenting means may be used, so far as concerns most features of the invention, and such a mechanism is shown in Fig. 11, for applying a washer to either side of a tag or flap. In Fig. 11, the stock *x* for one washer is fed forward between rolls 126 and 127, and is presented to any suitable form of washer die 128. On the other side the washer stock *y* is fed forward between rolls 129 and 130, and is presented to any suitable washer die 131.

Means are provided for grasping the free end of the string of the loose loop, and as embodied, a shaft 138 is journaled in brackets 139 and 140 (Figs. 8 and 9), mounted on the bed plate 97. Fixed to or formed on one end of the rod 138 is a gripper jaw 141, which cooperates with a fixed jaw 142, consisting of a plate mounted on the machine frame. The actuating means for jaw 141

comprises an arm 143, fixed to shaft 138. Pivotedly connected to arm 143 at 144 is a link 145, which is pivoted at its other end 146 to a lever 147. Lever 147 is pivotally supported at 148 on a standard 149, fixed to the machine frame. At its opposite end lever 147 has a cam roll 150, cooperating with a cam 151, which is fixed on the shaft 80. A spring 152 holds the cam roll to its cam.

Means are provided for furnishing an adequate supply of string to the loop-forming mechanism, and, as embodied, a pair of feed rolls 160 and 161 are journaled, respectively, at 162 and 163 in standards 164 and 165, which are carried on a bracket 166, supported from the machine bed 97. One of the rollers has fixed to its shaft a belt pulley 167, over which runs a belt 168, which also runs over a pulley 169, fixed on the shaft 80. The string goes from the feed rollers to a support and guide 172, mounted on the machine frame. Thus an adequate supply of loose string is provided for the mechanism during its travel and loop-forming movements.

Means are also provided by the invention for severing the desired length of string between the eyeleting means and the loop-forming means, this location and operation of the cutting means leaving the string supply in continuous engagement with, and under the continuous control of, the loop-forming mechanism.

As embodied (Figs. 8, 9 and 10), a fixed shear blade 176 is mounted at 177 upon the machine bed. A pivoted shear blade 178 is pivotally mounted at 179 upon the machine bed. At the lower end 180 thereof, the pivoted blade 178 is pivotally connected to a link 181, which link is longitudinally reciprocably supported, and it has a cam roll 184 working in an annular cam groove 185 formed in the hub of the pulley 169, which is fixed on the shaft 80.

The manner of operation of the mechanism just described is substantially as follows:—

The momentary presentation of the loose loop with its free end at the eyeleting and washer supplying station has already been described, and is shown in Fig. 6. Just at this moment the eyelet die plunger 121, carrying one of the washers and the eyelet in the usual manner, passes through the central aperture 26 in the loop-forming mechanism, and at this instant the jaw 141 closes down on the free end of the string, as shown in Figs. 6 and 7.

At the same moment, the traveling carrier 1 swings backwardly to the right in Fig. 8, and as the end of the string is held in gripper 141, 142, the tension on the string at spring 8 will cause spring 27 and disc 24 to yield, releasing the loop, and leaving the

string *a* turned once about the eyelet on die plunger 121 as shown in Fig. 7 and in the same manner as in the hand operation. The eyelet is upset in the usual manner. During 5 this return movement of the carrier arm 1 to the right in Fig. 8, it will be understood that the looping mechanism is idle and in position for the next looping operation, due to the pawl and ratchet 50 and 51, and that 10 the string *a* which is now held by the gripper 141, 142, will run freely through the holding spring 10. As the carrier arm 1 gets back to the position of Fig. 8, the shears 176, 178, will cut off the desired length of 15 string to the left of the carrier arm in Fig. 8, and on the same side thereof as the eyeleting mechanism. Thus the supply of string *a*, shown as a loose loop in Fig. 8, will be in absolutely the same relation, as 20 regards engagement and control, to the loop forming mechanism at all times, irrespective of the travel of the carrier, or of the forming of the loop. As the carrier moves toward the left in Fig. 8, the spring 25 10 will prevent the string from pulling out or changing its relation to the looping mechanism, and in fact there is never any strain on the loose loop of string which forms the reserve supply and which is preferably uniformly fed forward by the rolls 30 160 and 161.

The invention in its broader aspects is not limited to the specific mechanisms shown and described but departures may be made 35 therefrom within the scope of the accompanying claims without departing from the principles of the invention and without sacrificing its chief advantages.

What I claim is:—

40 1. A machine for attaching strings to tags, envelope flaps and the like, including in combination reciprocating means for forming a loose loop in the free end of a string and presenting the loop at the eyelet position and means for upsetting the eyelet.

45 2. A machine for attaching strings to tags, envelope flaps and the like, including in combination reciprocating means for forming a loose loop in the free end of a string and presenting the loop at the eyelet position and means for presenting an eyelet within the loop and upsetting the eyelet.

50 3. A machine for attaching strings to tags, envelope flaps and the like, including in combination means for forming a loose loop in the free end of a string and presenting the loop at the eyelet position, means for gripping the free end of the looped string after the loop is formed, and means for upsetting the eyelet.

55 4. A machine for attaching strings to tags, envelope flaps and the like, including in combination means for forming a loose

loop in the free end of a string and presenting the loop at the eyelet position, means for gripping the free end of the loop string after the loop is formed and before the eyelet is upset, and means for upsetting the eyelet. 70

5. A machine for attaching strings to tags, envelope flaps and the like, including in combination reciprocating means for forming a loop of string, an eyelet die plunger, means for moving the eyelet die plunger into the formed loop of string and means for upsetting the eyelet. 75

6. A machine for attaching strings to tags, envelope flaps and the like, including in combination reciprocating means for forming a loop of string, an eyelet die plunger, means for moving the eyelet die plunger into the formed loop of string, means for gripping the end of the formed loop of string, and means for upsetting the eyelet. 80

7. A machine for attaching strings to tags, envelope flaps and the like, including in combination means for forming a loop of string, an eyelet die plunger, means for moving the eyelet die plunger into the formed loop of string; means for gripping the end of the formed loop of string, after the eyelet die plunger is within the loop, and means for upsetting the eyelet. 85 90

8. A machine for attaching strings to tags, envelope flaps and the like, including in combination means for forming a loose loop in the free end of a string, an eyelet die plunger, means for moving the eyelet die plunger into the formed loop of string and means for upsetting the eyelet. 95 100

9. A machine for attaching strings to tags, envelope flaps and the like, including in combination means for forming a loose loop in the free end of a string, an eyelet die plunger, means for moving the eyelet die plunger into the formed loop of string, means for gripping the end of the formed loop of string; and means for upsetting the eyelet. 105 110

10. A machine for attaching strings to tags, envelope flaps and the like, including in combination means for forming a loose loop in the free end of a string, an eyelet die plunger, means for moving the eyelet die plunger into the formed loop of string, means for gripping the end of the formed loop of string after the eyelet die plunger is within the loop, and means for upsetting the eyelet. 115 120

11. A machine for attaching strings to tags, envelope flaps and the like, including in combination means for continuously retaining a string and for forming a loop therein, and means for subsequently upsetting an eyelet to fasten the already formed loop to a tag or flap. 125

12. A machine for attaching strings to tags, envelope flaps and the like, including 130

in combination means for continuously retaining a string and for forming a loop in the free end thereof, and means for subsequently upsetting an eyelet to fasten the 5 already formed loop to a tag or flap.

13. A machine for attaching strings to tags, envelope flaps and the like, including in combination means for continuously retaining a string and for forming a loop in the free end thereof, means for gripping the 10 end of the string of the formed loop, and means for subsequently upsetting an eyelet to fasten the already formed loop to a tag or flap.

14. A machine for attaching strings to tags, envelope flaps and the like, including in combination means for continuously retaining a string and for forming a loop therein, an eyelet die plunger, means for moving the 20 eyelet die plunger into the previously formed loop, and means for upsetting an eyelet to fasten the loop to a tag or flap.

15. A machine for attaching strings to tags, envelope flaps and the like, including in combination means for continuously retaining a string and for forming a loop in the free end thereof, an eyelet die plunger, means for moving the eyelet die plunger into the previously formed loop, and means 30 for upsetting an eyelet to fasten the loop to a tag or flap.

16. A machine for attaching strings to tags, envelope flaps and the like, including in combination means for continuously retaining a string and for forming a loop in the free end thereof, means for gripping the end of the string of the formed loop, an eyelet die plunger, means for moving the eyelet die plunger into the previously formed loop, 40 and means for upsetting an eyelet to fasten the loop to a tag or flap.

17. A machine for attaching strings to tags, envelope flaps and the like, including in combination means for forming a loose 45 loop in the free end of a string and presenting the loop at the eyelet position, means for upsetting the eyelet, and means for severing a desired length of string between the loop forming means and the eyelet upsetting means.

18. A machine for attaching strings to tags, envelope flaps and the like, including in combination means for forming a loose 55 loop in the free end of a string and presenting the loop at the eyelet position, means for presenting an eyelet within the loop and upsetting the eyelet, and means for severing a desired length of string between the loop forming means and the eyelet upsetting means.

19. A machine for attaching strings to tags, envelope flaps and the like, including in combination means for forming a loose 65 loop in the free end of a string and presenting the loop at the eyelet position, means

for gripping the free end of the looped string after the loop is formed, means for upsetting the eyelet, and means for severing a desired length of string between the loop forming means and the eyelet upsetting 70 means.

20. A machine for attaching strings to tags, envelope flaps and the like, including in combination means for forming a loop of string, an eyelet die plunger, means for moving the eyelet die plunger into the formed 75 loop of string and means for upsetting the eyelet, and means for severing a desired length of string between the loop forming means and the eyelet upsetting means. 80

21. A machine for attaching strings to tags, envelope flaps and the like, including in combination means for forming a loop of string, an eyelet die plunger, means for moving the eyelet die plunger into the formed 85 loop of string, means for gripping the end of the formed loop of string, means for upsetting the eyelet, and means for severing a desired length of string between the loop forming means and the eyelet upsetting 90 means.

22. A machine for attaching strings to tags, envelope flaps and the like, including in combination means for forming a loose 95 loop in the free end of a string, an eyelet die plunger, means for moving the eyelet die plunger into the formed loop of string, means for upsetting the eyelet, and means for severing a desired length of string between the loop forming means and the eyelet 100 upsetting means.

23. A machine for attaching strings to tags, envelope flaps and the like, including in combination means for continuously retaining a string and for forming a loop therein, means for upsetting an eyelet to fasten the loop to a tag or flap, and means 105 for severing a desired length of string between the loop forming means and the eyelet upsetting means.

24. A machine for attaching strings to tags, envelope flaps and the like, including in combination means for continuously retaining a string and for forming a loop in the free end thereof, means for gripping the 115 end of the string of the formed loop, means for upsetting an eyelet to fasten the loop to a tag or flap, and means for severing a desired length of string between the loop forming means and the eyelet upsetting means. 120

25. A machine for attaching strings to tags, envelope flaps and the like, including in combination means for applying a reenforcing piece to a tag or flap, means for forming a loop of string away from said applying means and presenting the loop thereto, and means for upsetting an eyelet to fasten the reenforcing piece and string to the tag or flap. 125

26. A machine for attaching strings to 130

- tags, envelope flaps and the like, including in combination means for applying a reenforcing piece to a tag or flap, means for continuously retaining a string and for 5 forming a loop of string away from said applying means and presenting the loop thereto, and means for upsetting an eyelet to fasten the reenforcing piece and string to the tag or flap.
- 10 27. A machine for attaching strings to tags, envelope flaps and the like, including in combination means for applying a reenforcing piece to a tag or flap, means for forming a loop of string away from said applying 15 means and presenting the loop thereto, means for upsetting an eyelet to fasten the reenforcing piece and string to the tag or flap, and means for cutting off a desired length of string between the loop forming 20 means and the eyelet upsetting means.
28. A machine for attaching strings to tags, envelope flaps and the like, including in combination means for applying a reenforcing piece to a tag or flap, means for 25 continuously retaining a string and for forming a loop of string away from said applying means and presenting the loop thereto, means for upsetting an eyelet to fasten the reenforcing piece and string to the tag or 30 flap, and means for cutting off a desired length of string between the loop forming means and the eyelet upsetting means.
29. A machine for attaching strings to tags, envelope flaps and the like, including 35 in combination means for applying a reenforcing piece to a tag or flap, means for forming a loop of string away from said applying means and presenting the loop thereto, means for grasping the end of the 40 string of the formed loop, and means for upsetting an eyelet to fasten the reenforcing piece and string to the tag or flap.
30. A machine for attaching strings to tags, envelope flaps and the like, including 45 in combination means for applying a reenforcing piece to a tag or flap, means for continuously retaining a string and for forming a loop of string away from said applying means and presenting the loop thereto, means 50 for grasping the end of the string of the formed loop, and means for upsetting an eyelet to fasten the reenforcing piece and string to the tag or flap.
31. A machine for attaching strings to tags, envelope flaps and the like, including 55 in combination means for applying a reenforcing piece to a tag or flap, means for forming a loop of string away from said applying means and presenting the loop thereto, an eyelet die plunger and means for moving it into the previously formed loop and 60 means for upsetting the eyelet to fasten the reenforcing piece and string to the tag or flap.
32. A machine for attaching strings to 65 tags, envelope flaps and the like, including in combination means for applying a reenforcing piece to a tag or flap, means for continuously retaining a string and for forming a loop of string away from said applying means and presenting the loop thereto, means for grasping the end of the string of the formed loop, an eyelet die plunger and means for moving it into the previously formed loop and means for upsetting the eyelet to fasten the reenforcing piece and string to the tag or flap.
33. A machine for attaching strings to tags, envelope flaps and the like, including in combination means for forming a loop in a string away from the eyeleting position 70 and moving the loop to the eyeleting position, and means for upsetting the eyelet.
34. A machine for attaching strings to tags, envelope flaps and the like, including in combination means for forming a loop in a string away from the eyeleting position and moving the loop to the eyeleting position, and means for upsetting the eyelet, and means for cutting off a desired length of string between the loop forming means and 80 the eyeleting means.
35. A mechanism for forming a loop in a string including in combination means forming an annular channelway, means for holding the string at a point away from its 90 end and means for turning the free end of string about said channelway.
36. A mechanism for forming a loop in a string including in combination means forming an annular channelway, means for holding the string at a point away from its end and means for loosely engaging and turning the free end of string about said channelway.
37. A mechanism for forming a loop in a string including in combination means forming an annular channelway, means for holding the string at a point away from its end and means for turning the free end of string about said channelway, and means for releasing the looped string from the channelway.
38. A mechanism for forming a loop in a string including in combination means forming an annular channelway, means for holding the string at a point away from its end, means for loosely engaging and turning the free end of string about said channelway, and means for releasing the looped string from the channelway.
39. A mechanism for forming a loop in a string including in combination means forming an annular channelway, means for holding the string at a point away from its end, means for turning the free end of string about said channelway, means for grasping the free end of the looped string, and means for releasing the looped string from the channelway.
40. A mechanism for forming a loop in 130

- 5 a string including in combination members forming an annular channelway, means for turning the free end of a string about the channelway, and means for separating the channelway forming members to release the formed loop.
- 10 41. A mechanism for forming a loop in a string including in combination members forming a concentric hollow passageway and a peripheral annular channelway, means for turning the free end of a string about the channelway, and means for separating the channelway forming members to release the formed loop and means for presenting a 15 rod within said concentric hollow passageway.
- 20 42. A mechanism for forming a loop in a string including in combination members forming a concentric hollow passageway and a peripheral annular channelway, means for turning the free end of a string about the channelway, means for separating the channelway forming members to release the formed loop, means for presenting a rod 25 within said concentric hollow passageway, and means for gripping the free end of the looped string.
- 30 43. A mechanism for forming a loop in a string including in combination members forming an annular channelway, means for turning the free end of a string about the channelway, and a resiliently yielding mounting for a channelway member to release the loop therefrom.
- 35 44. A mechanism for forming a loop in a string including in combination members forming a concentric hollow and a peripheral channelway, means for turning the free end of a string about the channelway, and a resiliently yielding mounting for a channelway member to release the loop therefrom.
- 45 45. A mechanism for forming a loop in a string including in combination a looper moving to and from eyeleting position, and having an open side through which the eyelet die plunger passes as the looper moves away.
- 50 46. A mechanism for forming a loop in a string including in combination a rotary looper moving to and from eyeleting position, and having an open side through which the eyelet die plunger passes as the looper moves away.
- 55 47. A machine for attaching strings to tags, envelope flaps and the like, including in combination means in continuous engagement with a supply of string for forming a loose loop in the free end of a string and presenting the loop at the eyelet position and means for upsetting the eyelet.
- 60 48. A machine for attaching strings to tags, envelope flaps and the like, including in combination means in continuous engagement with a supply of string for forming
- 70 a loose loop in the free end of a string and presenting the loop at the eyelet position, means for gripping the free end of the looped string after the loop is formed and before the eyelet is upset, and means for upsetting the eyelet.
- 75 49. A machine for attaching strings to tags, envelope flaps and the like, including in combination means in continuous engagement with a supply of string for forming a loose loop in the free end of a string, an eyelet die plunger, means for moving the eyelet die plunger into the formed loop or string, means for gripping the end of the formed loop of string, and means for upsetting the eyelet.
- 80 50. In a machine of the character described, the combination of an eyelet applying mechanism, and loop forming mechanism movable back and forth from the side into operative relation with the eyelet applying mechanism.
- 85 51. In a machine of the character described, the combination of an eyelet applying mechanism, and loop forming mechanism in continuous engagement with a supply of string movable back and forth from the side into operative relation with the eyelet applying mechanism.
- 90 52. In a machine of the character described, the combination of an eyelet applying mechanism, and loop forming mechanism movable back and forth from the side into operative relation with the eyelet applying mechanism, the loop forming mechanism turning as it moves toward the eyelet applying mechanism, for forming the loop.
- 95 53. In a machine of the character described, the combination of eyelet applying mechanism, loop forming mechanism movable back and forth from the side into operative relation with the eyelet applying mechanism, and string gripping mechanism for gripping the free end of the string, whereby the loop forming mechanism measures off a length of string as it moves away from the loop forming mechanism.
- 100 54. In a machine of the character described, the combination of eyelet applying mechanism, loop forming mechanism movable back and forth from the side into operative relation with the eyelet applying mechanism, and string gripping mechanism for gripping the free end of the string, the loop forming mechanism being in continuous engagement with the string and being adapted to rotate as it moves toward the eyelet applying mechanism for forming a loop, and being also adapted to measure off a length of string as it moves in the opposite direction.
- 105 55. In a machine of the character described, the combination of eyelet applying mechanism, loop forming mechanism con-

tinuously engageable with the string associated with the eyelet applying mechanism and relatively movable back and forth with respect thereto, and a string cutting device located between the initial position of the loop forming mechanism and the eyelet applying mechanism.

56. In a machine of the character described, the combination of eyelet applying mechanism, loop forming mechanism, continuously engageable with the string, relatively movable back and forth with respect to the eyelet applying mechanism, and a string cutting device for severing the string

15 at a point on the free end of the string.

57. In a machine of the character described, the combination of eyelet applying mechanism, loop forming mechanism continuously engageable with the string, associated with the eyelet applying mechanism and relatively movable back and forth with respect thereto, and a string cutting device for severing the string at a point on the string between the initial position of the

25 loop forming mechanism and the eyelet applying mechanism, said cutting device being operated just after the loop forming mechanism has measured off a length of string by returning to its starting position.

30 58. In a machine of the character described, the combination of eyelet applying mechanism, string gripping mechanism as-

sociated therewith, loop forming mechanism relatively movable back and forth with respect to the eyelet applying mechanism, and a string cutting device for severing the string.

59. In a machine of the character described, the combination of eyelet applying mechanism, string gripping mechanism as- 40 associated therewith, loop forming mechanism which engages the string continuously and is relatively movable back and forth with respect to eyelet applying mechanism, and a string cutting device for severing the string 45 after the looping mechanism has measured off a length of string by returning to its initial position.

60. In a machine of the character described, the combination of eyelet applying 50 mechanism, string gripping mechanism continuously engageable with a supply of string and reciprocable back and forth from the side into operative relation with the eyelet applying mechanism, the loop forming 55 mechanism forming a loop as it moves toward the eyelet applying mechanism, and measuring off a length of string as it moves in the opposite direction, and a cutting device for severing the string. 60

In testimony whereof, I have signed my name to this specification.

GEORGE W. SWIFT, Jr.
